UNITED STATES PATENT OFFICE.

MAURICE ANDRÉ LOUIS ROCHER, OF CHATELLERAULT, VIENNE, FRANCE.

VICE HAVING AN INSTANTANEOUS TIGHTENING AND LOOSENING ACTION.

1,406,901.

Specification of Letters Patent. Patented Feb. 14, 1922.

Application filed February 24, 1920. Serial No. 360,606.

(GRANTED UNDER THE PROVISIONS OF THE ACT OF MARCH 3, 1921, 41 STAT. L., 1313.)

To all whom it may concern:

Be it known that MAURICE ANDRÉ LOUIS ROCHER, a citizen of the Republic of France, residing at Chatellerault, Vienne, France, 5 27 Rue de l'Angelarde, has invented certain new and useful Improvements in Vises Having an Instantaneous Tightening and Loosening Action, (for which I have filed an application in France, August 29, 1918, Patent No. 491,889,) of which the following is a 10 specification.

This invention is directed to an improved vise in which the movable jaw is adjustable with relation to a fixed jaw through a rod 15 having threaded connection with said movable jaw, whereby to obtain an approximate adjustment of the jaws, the final clamping adjustment being secured through a cam movement, whereby to secure a quick action 20 in the final tightening or initial loosening of the jaws.

This vise is essentially characterized by the use of a movable jaw which may be drawn sufficiently near to the work to be machined, by means of a screw provided with a hand-wheel for determining the adjustment, when the first piece of work of a series begins to be operated upon, without however clamping the latter. The final clamping 25 of the said piece of work is then instantaneously obtained by a cam acting on the fixed jaw for causing an intermediate locking member and consequently the screw and the movable jaw to slide in the frame.

30 The amount of clamping obtained by the cam may be increased or diminished when the pieces of work to be machined are raw castings or forgings of varying thicknesses.

For reducing to a minimum the risks of 35 breaking of large pieces of work, the cam instead of acting directly upon the fixed jaw, acts upon a roller the axis of which has a cross section calculated in such a manner that a too powerful stress risks at most 40 to shear the latter.

In the accompanying drawings,

Fig. 1 is an elevation of the vise shown in its full open position;

Fig. 2 is an end view on the side of the 50 movable jaw;

Fig. 3 is a plan view;

Fig. 4 is an end view on the side of the fixed jaw;

Fig. 5 is a section made on line 5—5 of 55 Fig. 3,

Fig. 6 is a section made on line 6—6 of Fig. 5;

Fig. 7 is a section on line 7—7 of Fig. 3.

Fig. 8 is a section made on line a—b on the side of the fixed jaw only, illustrating a 60 means whereby the quick action feature is eliminated and the parts fixed for adjustment through the threaded rod only.

Fig. 9 is an elevation of the rocking jaw;

Fig. 10 is a section made on line 10—10 65 of Fig. 9.

Fig. 11 is a plan view of the said rocking jaw.

Figs. 12 and 13 illustrate a crank to be used only for the ordinary vise. 70

Figure 14 is a vertical section made on line 14—14 of Fig. 15 and illustrates a modification;

Figure 15 is a plan view of the modified construction; 75

Figure 16 is a view partly in elevation and partly in cross vertical section and

Figure 17 is a side view of the vise on the side where the cam is arranged.

The vise is constituted by a frame A in 80 which can move the movable jaw B which is held in the frame by the center plate C secured to the lower part of the jaw B.

Through a nut D, fitted in the jaw B, passes a screw E one end of which is provided with a head E' fitting in a recess E'' made in the immediate locking members J, K. This screw is operated by a milled nut Q secured on the end E''.

The member J serves as a support for a 90 cam N, provided with a heel N'' and which can be actuated by a tail piece N' by pivoting about a spindle O screwed in the member J.

A flange M secured by screws to the frame 95 will act as an abutment for the cam when releasing the device.

In the fixed jaw H is secured, by any suitable means a member L upon which acts during the rotation the cam N. 100

The operation of this vise will be as follows:

According to the thickness of the pieces of work to be clamped the movable jaw B is moved sufficiently near to the piece of 105 work (at about 20 millimeters therefrom), by means of the screw E which is actuated by the handle Q. This distance is adjusted for the entire series of pieces to be machined. The final clamping is obtained by acting on 110

the tail piece *N'* of the cam *N* for causing the latter to turn about its axis *O* and bringing the most eccentric portion in contact with the member *L*. By reason of the eccentricity of the cam, the member is pushed back and slides in the frame *A* drawing along the screw *E* and, consequently, the movable jaw *B*, which latter acts upon the piece of work to be clamped.

10 If by reason of a slight difference in the sizes of the piece of work to be machined, the latter is not slightly clamped, it will simply be necessary to impart a slight movement to the screw *E* for obtaining immediately a perfect clamping action.

15 The releasing of the piece of work is obtained by causing the cam to rotate in the reverse direction. In this movement the heel *N''* of the cam acts upon the flange *M*, secured to the frame, for pushing back the member *J* whereby the jaw *B* is moved away from the jaw *H*.

20 When it is desired to clamp pieces of work the surfaces of which are not parallel, it is simply necessary to remove the jaw *B* and to replace it by the jaw *R-S* shown in Figures 9, 10 and 11, the operation of the vise remaining the same.

25 The transformation into an ordinary vise is effected by removing the spindle *O* and the cam *N* and by securing the intermediate locking member to the frame by means of a screw *U* which is provided with a cylindrical part *U'* fitting in a hole *A'* in the frame *A*. The tightening and releasing of the jaw *B* are effected by means of the screw *E* the milled handle of which is replaced by a crank *P*.

30 The transformation into multiple use apparatus consists in replacing the existing jaws by other of suitable profiles.

The modification illustrated in Figures 14 to 17 allow:

35 1. The replacement of an ordinary jaw by a ball jaw the clamping portion of which may be instantaneously replaced by a clamping portion of suitable profile.

40 2. The construction of the fixed jaw by casting the same with bosses between which is adjusted the member carrying the clamping part and serving as a bearing for the cam during the clamping action. The cam acts upon a roller the axis of which has a cross section calculated in such a manner as to reduce the risks of breaking.

45 3. The progressive tightening and releasing of the vise by modifying the profile of the cam and by obtaining a permanent contact of the said cam on the roller serving for the tightening and on the flange serving for releasing the vise.

50 4. The protection of the screw threads of the screw in all its position by means of a protecting member surrounding the upper part.

The jaw *B* is provided with a recess *a* in which enters the part *b* 6 of the clamp *c*. The part *b* is held in place by the screw *d* which is screwed in the body of the jaw. The fixed and jointed clamps are both provided with the part *b* in the shape of a ball, but the jointed clamp utilizes this ball for placing itself parallel to the member to be clamped.

55 The connection of the two jaws is the same as in the first construction as well as the intermediate member *J*.

60 The cam *N* is secured by the spindle *O*, but instead of acting upon the fixed abutment *L*, acts upon a roller *e* the axis *f* of which has such a cross section that it will be sheared when the stress exerted by the cam will be too powerful. This axis *f* is secured in a part *g* adjusted between two bosses *h-i* integral with the frame *A*. The part *g* is held in position by the clamp *j* which is connected to the bosses *h-i* by screws or other suitable devices.

65 The cam *N* has a profile permitting the progressive tightening of the vise and maintaining it in permanent contact, on the one hand, with the roller *e* and, on the other hand, with the flange *M* which serves for releasing the vise. The smallest rotation in one direction or the other produces the displacement of the movable jaw.

70 The screw is protected from filings or other similar matter by a protecting member secured, on the one hand to a half-washer *l* carrying the smooth portion of the screw *E* and, on the other hand, on the bearing *m* fixed at the front portion of the frame *A*. This protecting member passes through the movable jaw in a small slot provided for that purpose.

Claims.

1. A vise comprising a frame plate formed with a longitudinal recess laterally enlarged in its lower portion to provide shoulders, a jaw carrying block slidably in said recess, a jaw carried thereby and slidably mounted on top of the frame plate, a second jaw fixed to the frame plate, an adjusting block slidably mounted in said recess below the fixed jaw, a rod mounted in the adjusting block for rotative movement only, said rod having threaded connection with the jaw carrying block, a cam element rotatably mounted on the adjusting block and having cam cooperation with the fixed jaw, and means cooperating with the shoulders of the recess to hold the jaw carrying block and cooperating parts in the recess.

2. A vise having a frame plate formed in the upper portion with a longitudinally extending open ended recess, the bottom of the plate having an interrupted recess communicating with the first mentioned recess, a jaw carrying block slidably mounted in

the first mentioned recess, a jaw carried thereby, a fixed jaw secured to the frame plate, an adjusting block mounted in the first mentioned recess, an operating rod 5 mounted for rotative movement in the adjusting block and having threaded connection with the jaw carrying block, an opening formed in the adjusting block, an opening formed in the frame plate with which

the opening in the block may register to receive means for securing the adjusting block with relation to the frame plate, a cam member carried by the adjusting block, and an abutment carried by the jaw fixed to the frame plate to be engaged with such cam 15 member.

In testimony whereof I affix my signature.

MAURICE ANDRÉ LOUIS ROCHER.
